UNITED STATES PATENT OFFICE

133,178

DESIGN FOR A STRAINER

Angus R. Gross, Baltimore, Md.

Application June 4, 1942, Serial No. 107,100

Term of patent 14 years

To all whom it may concern:

Be it known that I, Angus R. Gross, a citizen of the United States, residing at Baltimore, State of Maryland, have invented a new, original, and ornamental Design for a Strainer, of which the following is a specification, reference being had to the accompanying drawing, forming a part thereof.

In the drawing:

Fig. 1 is a front elevational view of a strainer showing my new design.

Fig. 2 is a top plan view thereof.

I claim:

The ornamental design for a strainer, substantially as shown.

ANGUS R. GROSS,
